(57) **CLAIM**

The ornamental design for a hair curler, as shown and described.

DESCRIPTION

1. Hair curler

1.1 is a perspective view showing the hair curler of our design;

1.2 is a front elevational view thereof;

1.3 is a rear elevational view thereof;

1.4 is a left side elevational view thereof;

1.5 is a right side elevational view thereof;

1.6 is a top plan view thereof; and

1.7 is a bottom plan view thereof;

2. Hair curler

2.3 is a perspective view showing the hair curler of our design;

2.2 is a front elevational view thereof;

2.3 is a rear elevational view thereof;

2.4 is a left side elevational view thereof;

2.5 is a right side elevational view thereof;

2.6 is a top plan view thereof; and

2.7 is a bottom plan view thereof; and

3. Hair curler

3.1 is a perspective view showing the hair curler of our design;

3.2 is a front elevational view thereof;

3.3 is a rear elevational view thereof;

3.4 is a left side elevational view thereof;

3.5 is a right side elevational view thereof;

3.6 is a top plan view thereof; and

3.7 is a bottom plan view thereof.
